MUFFLER

John J. Compo, Defiance, Ohio

Application October 14, 1931, Serial No. 568,789

1 Claim. (Cl. 137—160)

My invention has for its object to provide a muffler that is dependent upon the principle of silencing that inherently exists in reverse megaphone constructions. The invention provides an exceedingly simple construction whereby the explosive exhaust of internal combustion engines is practically silenced by reason of the progressive dissipation of the pressure of the explosive discharges. This produces substantially a constant stream from the muffler upon each discharge of the exhaust gases from the engine. The flow of the gas through the smaller ends of the megaphonic members may be restricted by a plurality of openings formed in the members to direct the gases into expansion chambers that again disperse them through openings in the smaller end of the said succeeding conical member.

The invention consists in other features and advantages which will appear from the following descriptions and upon examination of the drawing. Mufflers containing the invention may partake of different forms and may be varied in their details and still embody the invention. To illustrate a practical application of the invention, I have selected two mufflers embodying the invention as examples of various embodiments and the details thereof that contain the invention and shall describe the selected mufflers hereinafter, it being understood that variations may be made without departing from the spirit of the invention. The particular muffler selected is shown in the accompanying drawing.

Fig. 1 is a longitudinal section of one of the mufflers selected as an example. Fig. 2 is a longitudinal section of a second muffler selected as illustrative of the embodiment of my invention. Fig. 3 is a view of a section taken on the plane of the line 3—3 indicated in Fig. 1, and Fig. 4 is a view of a section taken on the plane of the line 4—4 indicated in Fig. 2.

In the particular forms of mufflers illustrated in the drawing, they are each provided with a cylindrical shell 1 having end walls 2 and 3 that have inlet and exhaust ports 4 and 5 that are surrounded by suitable sleeves or flanges 6 and 7 to enable connection with the exhaust pipes of the engine and with the tail pipe of the muffler. In the form of construction shown in Fig. 1, a pair of conical sheet metal members 10 and 11 are located within the cylindrical wall 1 or drum of the muffler. The larger ends of each of the cones 10 and 11 are located nearer to the inlet port than the smaller ends

of the cones and are acetyline welded to the drum to prevent blowing or bursting of the muffler. The outer ends of the cones tightly fit the inner surface of the drum 1. The cone 10 is located contiguous to the inlet port 4 while the larger end of the cone 11 is located in proximity to the plane of the smaller end of the cone 10 and the smaller end of the cone 11 is located in slightly spaced relation with respect to the outlet port 5. The smaller ends of each of the cones 10 and 11 are provided with vanes 14. In the form shown, the vanes fit the smaller end portions of the cones 10 and 11 and are so formed that four radiating vanes are produced and extend at right angles to each other. The corners formed between the vanes are located in the axes of the cones 10 and 11 and the outer edges of the vanes fit the inner surfaces of the end portions of the cones.

The gas entering the cylindrical form 1 through the inlet port 4 has opportunity to expand to a limited degree within the larger end of the cone 10. A whirling movement of the gas is also produced which greatly reduces the speed of its forward movement. Immediately after the first expansion, the gas is directed in the form of a stream towards the outlet of the cone 10 and through the spaces that are formed between the vanes 14 and the inner surface of the smaller end portion of the cone 10, which produces a plurality of definitely directed streams that pass through the openings 16 formed by the vanes 14 located in the smaller end of the cone 10. This greatly reduces the degree of expansion or pressure of each stream that takes place upon the escape of the gases from the small end of the cone 10. The vanes operate to produce definitely directed streams that are permitted to expand or escape from the cones and counteract each other laterally as they are allowed to escape into the larger spaces, which produces conflict between the sudden, although greatly reduced, expansion of each of the streams. The whirling of the gas is checked as it enters the larger end of the cone 11 and passes to the smaller end. The gas is then subjected to the same conditions to which it was subjected in the cone 10 and the same reactions occur to further reduce the localized pressures and produce a uniform delivery and straight line or axial pressure at the smaller end of the cone 11 as distinct from a whirling movement and lateral at the smaller end of the cone 11. The gas passes through the outlet port 5

5 of the muffler in a substantially continuous stream of substantially uniform pressure.

In the form of construction shown in Fig. 2 the cylindrical shell 1 is provided with a pair of sheet metal cones 20 and 21. The cones 20 and 21 are secured in positions that are similar to the positions that the cones 10 and 11 are secured in the form of construction shown in Fig. 1. The smaller ends of the cones in the form of construction shown in Fig. 2 are closed except as they may be opened by a controlling valve and except as the gas is subdivided and directed laterally into the chambers that are formed between the cones 20 and 21 and the drum 1. The smaller ends of the cones are each provided with a row of openings 22 that are formed in the walls of the smaller end portions of the cones. The gas entering through the port 4 is first allowed to expand within the larger end of the cone 20 and, as it contracts is allowed to escape through the openings 22 of the cone 20 into the chamber 23. It then enters the cone 21 and again is allowed to escape through the openings 22, formed in the wall of the smaller end portion of the cone 21, into the chamber 24, formed between the cone 21 and the cylinder 1. In order to direct the gas through the openings 22 in the cones 20 and 21, the smaller end of the cones are connected by means of a pipe 25 formed of sheet metal. The end of the pipe, located in the smaller end of the cone 21, is closed by a valve 27 that may be operated by means of a suitable arm and link 28 to open the valve to enable a direct movement of the exhaust products of the engine

through the muffler. When, however, the valve 27 is closed, the gas is disbursed through the openings 22, first from the cone 20 and then from the cone 21.

The smaller end of the cone 20 is provided with the vanes 14 that direct the gas towards the small openings 22. They operate to prevent whirling movement of the gas in the vicinity of the openings 22 and thus enable the gas to escape through the openings. This reduces the pulsating movement and pressure of the gas and produces substantially a uniform movement and continuous flow of the gases from the outlet port of the muffler.

I claim:

In a muffler, a cylindrical drum having inlet and outlet ports, a pair of sheet metal cones located substantially end to end and within the drum and having a total length substantially equal to the length of the drum, the larger ends of the cones located nearer the inlet port of the drum than the smaller ends of the cones, the larger ends of the cones fitting the surfaces of the drum, a plurality of partitioning members positioned in the smaller end of one of the said cones and forming openings forming passageways into the larger end of the other of said cones and into the space between the said other of the cones and the wall of the said drum, the larger end of the said other cone being open and without an end wall, the said partitioning members forming means for preventing the whirling of exhaust gases in the vicinity of the smaller ends of the said cones.

JOHN J. COMPO. 35
